UNITED STATES PATENT OFFICE.

GEORGE L. PRICHARD AND HERBERT HENDERSON, OF PORT ARTHUR, TEXAS, ASSIGNEES TO GULF REFINING COMPANY, OF PITTSBURGH, PENNSYLVANIA, A CORPORATION OF TEXAS.

OIL-HEATING FURNACE AND THE LIKE.

Application filed February 28, 1922. Serial No. 539,966.

To all whom it may concern:

Be it known that we, GEORGE L. PRICHARD and HERBERT HENDERSON, citizens of the United States, and residents of Port Arthur, in the county of Jefferson and State of Texas, have invented certain new and useful Improvements in Oil-Heating Furnaces and the like, of which the following is a specification.

10 This invention relates to oil heating furnaces and the like and it comprises a heating chamber, oil containing means located therein, a fire box in communication with the chamber, and means for regulating the passage of fire gases through the chamber and around the oil container; all as more fully hereinafter set forth and as claimed.

15

In the generation of steam in boilers it is customary to heat the boiler to as high a 20 temperature as possible and to circulate the gases around the boiler, the gases leaving the heating zone at as low a temperature as possible. Particularly in vertical water tube boilers the lower part of the tubes are heated 25 to high temperatures and the upper part of the tubes are heated to lower temperatures with the gases or products of combustion which have previously heated the lower parts of the tubes. Such a method of heating 30 is economical and advantageous in steam generating boilers, the object being to absorb as many heat units as possible.

In heating oils and the like, particularly 35 for the purpose of cracking higher boiling hydrocarbons into lower boiling hydrocarbons, it is desirable to heat the whole body of oil undergoing cracking to a uniform temperature, whether this be a relatively low temperature around 650° to 800° F. or higher 40 temperatures—as high as 1500° F. Uniform heating prevents excess deposition of carbon or local overheating and permits accurate control of operation.

Among other objects of our invention is 45 the provision of a furnace adapted for uniform and regular heating of oils and the like.

In the accompanying drawings we have 50 shown one form of a specific embodiment of our invention.

Figure 1 is a vertical transverse section through our furnace, certain parts being shown in elevation;

Figure 2 is a vertical section at right an-

gles to Figure 1 taken along the breechings 55 leading to the flue and

Figure 3 is a section along line 3—3 of Figure 2.

Referring to the drawings 1 indicates the brick supports upon which is mounted the 60 fire box 2 having the fire brick walls and roof 3 and provided with the door 4 for air or an oil and gas burner and with the oil and gas burner 5. The fire box is provided with the vertical shaft 6 separated from the 65 fire chamber 7 by means of the wall 8, such wall being provided with a plurality of openings 9 spaced at intervals along its length. Beams 10, surrounded by brick-work, support, at their tops, beams 11 suitably braced by angle irons 12; and supported from the beam 11 by means of the bolts 13 and ears 13' is the upper drum 14 of the 70 tubular boiler-like arrangement. The drum 14 is connected to the lower drum 15 by means 75 of a plurality of tubes 16, the whole being suspended in the chamber 7 in such manner that contraction and expansion are well taken care of.

Leading from the heating chamber 7 at 80 intervals along the height thereof are the plurality of breechings 17, 3 sets being shown. In the embodiment illustrated, each set may comprise 4 breechings 17 (shown in Figure 3) parallel to the upper and lower drums 14 and 15, all these breechings leading to the flues 18 which in turn communicate with the stack 19. Each of the breechings is provided with a valve or damper 20 having the shafts 21 to which may be attached pulley wheels or the like driven by the chains or ropes 22 leading outside the furnace.

The heating chamber 7 receiving fire gases 95 from the fire box is provided with a plurality of baffle plates 23 at different heights making in effect (in the embodiment shown) three independent heating chambers designated A, B and C, each of these chambers in communication with four of the breechings 17.

By proper adjustment of the dampers 20 in the breechings, the volume of the fire gases passing the tubes through chambers A, B and C may be regulated. This permits 105 regulation longitudinally of the tubes. By regulating the valves in any one of the four parallel breechings at the same elevation,

transverse regulation across the set of the tubes is also possible. In the embodiment shown there are 12 breechings with independently operated dampers, but it is to be understood that our invention is not limited to this number of dampers or to the number of breechings described. The chambers A, B and C are provided with the normally closed peep-holes 24 for observation of temperature by color in which event the dampers in the different breechings may be manually regulated; but ordinarily we provide thermostats shown diagrammatically at 26 which may be of the ordinary construction and which may record the temperature at these different points. The thermostats may be arranged to automatically control the dampers in the breechings. The specific construction of the thermostat 20 is not a part of our invention and any form found on the market may be used for our purposes, as well as any form of automatic control.

Under the furnace we provide compartments 27 having the door 28 and the sloping floors 29 provided with a drain pipe 30 for carrying away oils and the like when the furnace is down for repair or in the event of one of the tubes breaking. We 30 advantageously cover the fire-brick fire box, shaft wall and the breeching walls with red brick 31.

Oil may be admitted to the lower drum by inlet 32, and vapors sent by lines 33 from the upper drum to condensers (not shown).

In operation the furnace is fired preferably by burner 5 with air admitted through opening 4" from air flue 4', the products of combustion thus being sent along the roof of the fire box and then up the shaft 6. Or the burner may be used in burner hole 4. All the dampers in the breechings may be opened at this time and as local overheating occurs or as it is discovered that parts of the tubes are not being heated to the required temperatures, the dampers in the breechings are regulated accordingly. With thermostats set to regulate the dampers in accordance with the temperature of the firing gases entering each breeching, automatic control results. A temperature of 1400° F. is satisfactory for cracking gas oil and the like.

It will be noted that we have provided for what may be termed vertical as well as transverse regulation of the fire gases from one fire box for the whole set of tubes of the boiler-like construction and through

the independently operated dampers in the breechings, we may accurately control the passage of fire gases past the tubes at any height or at any point along their height before these gases reach the stack.

Since the gases leaving the flues are at relatively high temperatures their heat may be utilized elsewhere by closing damper 34 leading to the stack 19 and opening damper 35 in the flue 36 leading to a heater of any known type, such as a preheater for 70 boilers and the like.

What we claim is:—

1. A furnace comprising a fire box, a vertical shaft, means for dividing the shaft into a plurality of vertically spaced compartments, 75 a liquid container extending through the said compartments, ports in the wall of said shaft and in communication with the fire box, whereby heating gases from the fire box may be admitted to the said compartments, breechings leading from the compartments of said shaft, dampers in said breechings, a stack, and flues leading from the breechings to the stack.

2. A furnace comprising a fire box, a vertical shaft, means for dividing the shaft into a plurality of vertically spaced compartments, a liquid container extending through the said compartments, ports in the wall of said shaft and in communication with the fire box, whereby heating gases from the fire box may be admitted to the said compartments, a plurality of horizontally spaced breechings leading from each compartment of said shaft, dampers in said 90 breechings, a stack, and flues leading from the breechings to the stack.

3. A furnace comprising a vertical shaft, the walls on one side being provided with ports for admitting fire gases to the shaft 100 throughout its length, and the wall on the other side being provided with a plurality of vertically spaced breechings, whereby products of combustion may be admitted to the shaft substantially throughout its 105 length and may be withdrawn from the shaft at several different points along its length, a stack, and flues leading from said breechings to said stack, a fire box, and means for conducting products of combustion 110 from the fire box to the said ports in the wall of the shaft.

In testimony whereof we have hereunto signed our names at Port Arthur, Texas, this 25th day of February, 1922.

GEORGE L. PRICHARD.
HERBERT HENDERSON.
